UNITED STATES PATENT OFFICE.

CHARLES W. HINMAN AND WALTER HIBBARD HINMAN, OF WINCHESTER, MASSACHUSETTS.

GAS-METER.

1,221,179.

Specification of Letters Patent.

Patented Apr. 3, 1917.

Application filed April 27, 1916. Serial No. 93,874.

To all whom it may concern:

Be it known that we, CHARLES W. HINMAN and WALTER HIBBARD HINMAN, both citizens of the United States, residing at 5 Winchester, in the county of Middlesex and State of Massachusetts, have invented certain new and useful Improvements in Gas-Meters; and we do hereby declare the following to be a full, clear, and exact description of the invention such as will enable others skilled in the art to which it 10 pertains to make and use the same.

The present invention relates to gas-station meters of the class commonly known as "wet meters." The object of the present invention is to improve the construction of the type of meter disclosed in the prior Patents No. 638,457, and No. 638,458, granted December 5, 1899, with a view to rendering 15 the same of greater strength and rigidity, reducing the energy required for operation, and increasing both the cubical capacity and the speed of rotation and consequently the measuring capacity.

With these and other objects in view, as will appear from the following description, the present invention consists of the devices and combinations of devices hereinafter described, and more particularly defined in the 20 claims.

In the accompanying drawings which illustrate what is now considered the preferred form of the present invention, Figure 1 is a vertical longitudinal section of our improved meter; Fig. 2 is an oblique perspective of the revolving drum, with a portion of the shell broken away and other parts omitted for the sake of clearness; Fig. 3 is a transverse vertical section on line 3—3 25 of Fig. 1, with the diagonal braces which extend toward the outlet end of the drum omitted; Fig. 4 is an end elevation on a reduced scale of the outlet or left-hand end of the revolving drum, as shown in Fig. 1; and Fig. 5 is a perspective of one of the division 30 walls and end walls connected therewith.

The improved gas meter illustrated in the drawings comprises a stationary cylindrical casing 1 having at one end the axial gas inlet pipe or "dry-well" 2 and the outlet pipe 3 near the periphery. It is provided in its interior with the bearings 4 for the shaft 5 of the revolving measuring drum, the greater part of which is submerged beneath the 35 water which fills the casing 1 to a level

slightly below the upturned end of the inlet pipe 2, as indicated in Fig. 1.

The revolving drum comprises the cylindrical shell 7 provided on its interior with division walls to form the measuring compartments or pockets, and is rigidly supported upon the shaft 5 by means shortly to be described.

The division walls, of which there are four in the meter illustrated in the drawings, are composed of a plurality of sections, as shown best in Fig. 5, the alternate sections, such as 8, 9, and 10, being angularly disposed with relation each to the other with the middle section 9 co-planar with the axis, 40 and the end sections parallel to the axis. Adjacent and between these sections are other sections 11, 12, 13, and 14, all oblique to the axis of the drum, and angularly arranged with relation to each other. Extending along the inner edges of the sections 8, 9, and 10 is the radial portion 15, which is co-planar with the axis of the drum and with the section 9. The inner edge of this radial portion never rises above the level of 45 the water in the casing, its highest position being as shown in Fig. 1.

The inlet end of the division wall is provided with the end wall 16 which is nearly perpendicular to the axis of the drum and is 50 connected with the inlet end section 14 of the division wall by the curved section 17. The end wall 16 is provided with the right angle portions 18 and 19 parallel to the axis 55 of the drum which form the internal walls or partitions of one of the pockets 20 which surround the "dry well," as shown in Fig. 1.

The outlet end of the division wall is provided with the perpendicular end wall 21 connected to the outlet end section 11 of the 60 division wall by the curved section 22.

The inlet and outlet end walls extend at substantially right angles to one another, the advancing edge 23 of the inlet end wall 16 of one partition or division overlapping the 65 curved connecting section 17 of the division wall next in advance in the direction of rotation of the drum, thus forming between the edge and the section a long port for the entrance of gas into the measuring compartment as the inlet end wall rises above the water level. In a similar manner the following edge 24 of the outlet section 21 overlaps the curved connecting section 22 of the 70 next following division wall, to form the 75 100 105 110

elongated outlet port 25 (see Fig. 4) through which the gas can escape from the pocket in the drum out into the casing after the inlet end wall has dipped below the water level to close the inlet port.

The inlet end of the drum is closed, except for the axial opening for the inlet pipe, by the head or disk 26 connected with the shell 7 and the portions 18 and 19 extending from the inlet end wall 16, the outer portion of the head or disk thus closing the side of the pockets 20 in the inlet end of each measuring compartment, while the inner portion forms the side wall of the inlet chamber 15 into which the gas is delivered from the pipe 2 and from which the gas passes into the measuring compartments successively as their respective inlet ports rise above the water level.

The cylindrical shell with its division and end walls is supported as follows: Fixed upon the shaft 5 at or near each end of the drum is a hub 30 having an octagonal periphery and the four spokes 31 extending radially therefrom. Rigidly secured to these spokes are the radial angle iron arms or supports 32, which at their outer ends are attached to an angle iron ring 33 on the inner surface of the shell, there being a coöperating flat ring 34 on the outer surface of the shell. Rivets or other securing means passing through the rings and the shell hold the parts securely together. The radial arms 32 are further supported each by a short inclined brace 35, also formed of angle iron, and extending tangentially from the periphery of the hub 30 to the radial arm 32.

The middle of the drum or shell is supported from an intermediate hub 36 like the end hubs 30, having the same radial spokes 37, angle iron arms 38, and tangential braces 39, and the shell being provided with the internal angle iron ring 40, and external flat ring 41. The radial arms 38 lie in the plane 45 of the middle section 9 of the division walls, and also of the inner section 15, being secured to said sections by riveting or in other suitable manner.

The drum or shell is further supported by means of the diagonal braces 42 of angle iron, extending from the middle or intermediate hub 36 to the angle iron rings 33 at each end of the drum. These diagonal braces are secured to the flat faces on the hub and are so arranged that each brace supports one of the sections 8 or 10 of the division walls, being riveted thereto.

In order to increase the gas space in the casing above the water level without increasing the size of the casing, the bearings 4 are eccentrically located in the casing, being slightly lowered, as shown in Fig. 1, so that the periphery of the revolving drum comes nearer to the bottom of the casing than it does to the top.

The mode of operation of our improved meter is like that described in the prior patents above referred to, the gas entering through the inlet pipe or "dry well" from which it passes into the inlet chamber and thence into each measuring compartment or pocket formed between the adjacent division walls of the revolving drum as the inlet port rises above the water. The pressure of the gas on the leading wall of the compartment causes the drum to revolve until the compartment is entirely above the water level except the inner edge of the long radial section of the wall. The compartment is now completely filled with gas and as the drum continues to revolve the inlet port is carried beneath the water level, after which the outlet port rises, permitting the gas to escape through the outlet port into the gas space between the drum and the casing and to flow back toward the inlet end to the outlet pipe 3.

The cubical capacity of the compartments being known, it is only necessary to count the number of revolutions of the drum to measure the gas passing through the meter and this registering can be done by any suitable devices.

By forming the division walls of a plurality of differently inclined sections with their inner edges in line and substantially parallel to the axis of the drum, and with intermediate or adjacent sections obliquely inclined to the axis, and to one another, a wall is provided which, approximating a spiral on its outer portions, not only imparts a high degree of strength and rigidity to the drum, but also offers a minimum of resistance as it enters or leaves the water, thus reducing the power required to force the division walls through the water and permitting a higher rotative speed with corresponding increase in measuring capacity without danger of distortion or damage to the drum. These are matters of importance as meters of this type are of large size, up to sixteen or more feet in diameter, and have to operate under a very low pressure of gas, say ten to twenty inches of water gage, with not over four inches of absorbed pressure.

The provision of the radial portion or section extending substantially the length of the wall is also a feature of advantage as it imparts additional strength and rigidity to the walls and increases the effective measuring capacity of each compartment or pocket.

The method of supporting and bracing the drum is also a feature of the present invention as it affords a light, strong, and rigid structure which holds the drum firmly in shape, permitting lighter weights and higher rotative speeds than have been possible with prior constructions.

In our improved meter owing to the use of the internal angle iron ring and the external

flat ring and to the greater strength and rigidity of the revolving drum, less clearance has to be provided between the shell and the casing. Furthermore, the eccentric 5 mounting of the drum results in either increased gas space at the top of the drum or the use of a larger drum with the customary amount of gas space, without increasing the size of the stationary casing.

10 While we have shown and described what is now considered to be the preferred form of the present invention, it is to be understood that the form and arrangement of its parts may be varied, and that its different features 15 as defined by the claims are susceptible of separate embodiment.

Having thus described the present invention, what is claimed is:

1. In a gas meter the combination with a 20 stationary casing of a revolving drum comprising a cylindrical shell having internal division walls, each wall comprising a plurality of alternate sections angularly disposed with relation to one another, and having 25 their inner edges parallel to the axis of the drum, and a plurality of adjacent sections each being obliquely disposed relatively to the axis and to the other sections, and means for rotatably supporting the 30 drum in the casing.

2. In a gas meter the combination with a 35 stationary casing of a revolving drum comprising a cylindrical shell having internal division walls, each wall comprising a plurality of outer sections angularly disposed one to another, and an inner section parallel to the axis and extending substantially the length of the wall, and means for rotatably supporting the drum in the casing.

40 3. In a gas meter the combination with a stationary casing of a revolving drum comprising a cylindrical shell having internal division walls, each wall comprising a plurality of outer sections angularly disposed 45 one to another, and an inner section extending substantially the length of the wall, and means for rotatably supporting the drum in the casing.

4. In a gas meter the combination with a 50 stationary casing of a revolving drum comprising a cylindrical shell having internal division walls, each wall comprising a plurality of outer sections angularly disposed each to the others, and an inner plane 55 section located in the plane of the axis and extending substantially the length of the wall, and being co-planar with one of the outer sections, and means for rotatably supporting the drum in the casing.

60 5. In a gas meter the combination with a stationary casing of a revolving drum comprising a cylindrical shell having internal division walls, each wall comprising a plurality of outer plane sections angularly 65 disposed to one another, and parallel to the

axis of the drum, adjacent outer plane sections each obliquely disposed to the axis and to the other sections, and an inner plane section co-planar with the axis and extending substantially the length of the wall, and 70 means for rotatably supporting the drum in the casing.

6. In a gas meter the combination with a stationary casing of a drum mounted to revolve therein and comprising a cylindrical 75 shell having internal division walls, a shaft, a hub secured to the shaft, arms extending from the hub to the shell, and braces extending tangentially from the hub to the arms at points between the inner and outer edges 80 of the division walls.

7. In a gas meter the combination with a stationary casing of a drum mounted to revolve therein and comprising a cylindrical shell, a shaft, a hub secured to the shaft, 85 spokes formed integrally with the hub and extending radially therefrom, arms secured to the spokes and extending radially to the shell, and braces from the hub to the arms.

8. In a gas meter the combination with a 90 stationary casing of a drum mounted to revolve therein and comprising a cylindrical shell, a shaft, a hub secured to the shaft, arms extending from the hub, a ring on the inner surface of the shell and attached to 95 the outer ends of the arms, a ring on the outer surface of the shell opposite the first mentioned ring, and means for securing the rings together with the shell between them.

9. In a gas meter the combination with a 100 stationary casing of a drum mounted to revolve therein and comprising a cylindrical shell, a shaft, a hub secured to the shaft between the ends of the drum, arms extending 105 radially and diagonally from the hub to the drum, partition walls within the drum having a plurality of plane sections angularly arranged with respect to each other and parallel to the axis of the drum, certain of the sections being co-planar with and secured to said radial and diagonal arms.

10. In a gas meter the combination with a stationary casing of a drum mounted to revolve therein and comprising a cylindrical shell, a shaft, a hub secured to the shaft between the ends of the drum, arms extending 115 radially and diagonally from the hub to the drum, and rings on the shell to which the arms are secured.

11. In a gas meter the combination with a 120 stationary casing of a revolving drum comprising a cylindrical shell having internal division walls, a shaft upon which the drum is mounted, and bearings for the shaft eccentrically mounted with respect to the casing to bring the drum nearer to the bottom 125 of the casing than to the top.

12. In a gas meter the combination with a stationary casing of a revolving drum comprising a cylindrical shell having internal 130

division walls, each wall comprising a plurality of sections having their end edges converging in the direction from the axis of the drum toward the periphery, and a plurality of intermediate sections located alternately between the outer sections, and angularly disposed with relation thereto, and having their end edges diverging in the said direction, and means for rotatably supporting the drum in the casing.

13. In a gas meter the combination with a stationary casing of a revolving drum mounted to revolve therein, and comprising

15 a cylindrical shell, a shaft, a hub between the ends of the drum having a polygonal periphery, partition walls within the drum having a plurality of sections angularly arranged with respect to each other, certain of the sections being co-planar with certain of the faces on the periphery of the hub, and 20 diagonal braces secured to such co-planar faces on the hub and sections of partition walls.

CHARLES W. HINMAN.
W. HIBBARD HINMAN.
